UNITED STATES PATENT OFFICE.

GUSTAF WAHLSTROM, OF DES MOINES, IOWA.

WINDOW FRAME AND SASH.

SPECIFICATION forming part of Letters Patent No. 761,733, dated June 7, 1904.

Application filed July 24, 1903. Serial No. 166,862. (No model.)

To all whom it may concern:

Be it known that I, GUSTAF WAHLSTROM, a citizen of the United States, residing at Des Moines, in the county of Polk and State of Iowa, have invented certain new and useful Improvements in Window-Frames and Sashes Therefor, of which the following is a specification.

My objects are to provide a device of this class having an inner and an outer sash containing glass with an air-space between them so arranged as to form tight joints with the window-frame when the sashes are in their closed position, and, further, to provide an outer window-sash capable of moving downwardly below the window-sill and forming with the window-sill a water-tight joint either when the sash is in its closed or in its open position; and my object is, further, in this connection to provide water-tight packing-strips to engage the glass of the sashes, so that a water-tight joint is formed with the glass when the sash is at any point throughout its limit of movement.

A further object is to provide a window-screen in the same window-frame capable of sliding downwardly into the window-frame and so arranged as to form with the window-frame and the inner sliding sash a tight joint 30 when either in its closed or in its opened position.

My invention consists in certain details in the construction, arrangement, and combination of the various parts of the device whereby the objects contemplated are attained, as hereinafter more fully set forth, pointed out in my claims, and illustrated in the accompanying drawings, in which—

Figure 1 shows a vertical sectional view on the indicated line 1 1 of Fig. 2 through the window-frame and sashes and screen. Fig. 2 shows a horizontal sectional view of same on the indicated line 2 2 of Fig. 1. Fig. 3 shows a vertical central sectional view of a window-frame, sliding sashes, and screen of a modified form. Fig. 4 shows a vertical sectional view of a window-frame, sashes, and screen of a modified form, taken on the indicated line 4 4 of Fig. 6. Fig. 5 shows a vertical sectional view of the window-frame of said modified form, taken on the indicated line 5 5 of

Fig. 6. Fig. 6 shows a horizontal sectional view of the window-frame, sashes, and screen, illustrating the same modification shown in Figs. 4 and 5 and taken on the indicated line 55 6 6 of Fig. 4; and Fig. 7 shows a perspective view of the outer sliding sash used with the preferred form shown in Figs. 1 and 2.

Referring to the accompanying drawings, and particularly to the preferred form shown 60 in Figs. 1 and 2, I have used the reference-numeral 10 to indicate the top piece of the window-frame. 11 indicates the outer portion of the sill or bottom of the window-frame, and 12 the inner portion of the sill. The numeral 13 indicates the sides of the frame. In this form of my invention the sashes and screen are intended to slide downwardly, and hence I have provided space in the wall in which the window-frame is placed below the 70 window-frame. The reference-numeral 14 indicates the outer portion of the hollow wall, and 15 the inner portion, the space between the outer and inner portions being large enough to admit both the sliding sashes and 75 the sliding screen.

Erected on the inner faces of the sides 13 of the frame are the casings to receive the sides of the outer sliding sash. These casings on the opposite sides of the frame are exactly 80 alike and each comprises the side pieces 16 and 17, the outer ends thereof being secured to the part 13, and attached to the inner ends thereof are the narrow strips 18 and 19, with a space between them of a size to permit a 85 pane of glass to enter between them and freely slide. Secured to the inner face of the part 19 is a strip 20, and a rubber packing-strip 21 is held between the strip 20 and the part 19. This rubber strip projects inwardly into the 90 opening between the parts 18 and 19.

The outer sash, as clearly illustrated in Fig. 7, comprises a top piece composed of a central strip 22 and two short side strips 23. The sides are indicated by the reference-numeral 24, and a slight space is left between the ends of the parts 23 and the sides 24. The bottom of the sash is indicated by the numeral 25 and the glass panel by the numeral 26. On the outer face of the bottom of the sash 100 is a strip 27 to hold the glass in the bottom piece and to engage the under surface of the

sill 11 when the sash is elevated, as shown in Fig. 1. The sash is connected with the frame by having its sides 24 slidably mounted in the space between the parts 16 and 17, with 5 the rubber strips 21 engaging the front face of the pane of glass, and the bottom 25 is placed beneath the sill 11, so that the strip 27 engages the under portion of this sill 11 when the outer sash is at its upper limit, as shown 10 in Fig. 1. Secured to the top of the sill 11 is a packing-strip 28 to engage the front of the pane of glass, so that as the sash slides upwardly and downwardly in the window-frame this strip 28 will form a water-tight 15 joint with the pane of glass, and when the front sash is at its downward limit of movement the strip 28 will overlap the strip 27 and form a water-tight joint with said strip 28, as clearly shown by dotted lines in Fig. 1. 20 By this arrangement of parts it is obvious that the outer sash when in its closed position will form a water-tight joint both with the casing at the sides of the frame and with the sill of the window-frame, because the 25 packing-strips 21 and 28 will engage the sides and bottom of the panel of glass, and said strips will continue to stand in engagement with the pane of glass throughout its entire movement, and when the outer sash is at its 30 downward limit of movement the overhanging strip 23 will prevent water from entering under said strip 23.

The reference-numeral 29 indicates a pulley 35 above the outer sash, and a rope 30 is attached to the sash and passed over said pulley, said rope being attached to a weight 31 at the outer side of the side pieces 13 of the frame, as shown in Fig. 2. A similar weight is provided on the opposite side, and said weights 40 are designed to counterbalance the weight of the outer sash, so that it will be held in any position in which it may be placed.

The second sliding sash is held in place between the strips 16 and the stops 32. This 45 inner sash is composed of sides 33, slidably mounted between the strips 16 and the stops 32, and the top and bottom of the inner sash project forwardly at 34 enough to engage the inner faces of the front sash, as clearly shown 50 in Fig. 1. This sash is also provided with ropes and pulleys the same as the outer one.

Immediately in the rear of the stops 32 is a screen composed of sides 35 and top and bottom pieces 36. These sides slide between the 55 stops 32 and the stops 37 and the parts 36 and are wide enough to engage the rear of the top 34 of the inner sash, and the bottom 36 is of a width to engage the bottom of the middle sash and the front of the sill 12, and a screen 60 38 of the ordinary kind is placed in this frame. This screen is capable of sliding vertically and may be held at various points of elevation by means of the spring-stop 39 of ordinary construction. (Clearly shown in Fig. 2.)

65 One of the principal objections to window-

sashes that open by sliding in any direction except upwardly is that when opened or partly opened rain may enter the window-frame through the openings in which the sashes slide. This is highly objectionable, and for 70 that reason I have provided the structure before described and in use with the form of window-frame and sash just described. It is obvious that when the sashes are in their closed position, as shown in Fig. 1, then water will be prevented from entering through the openings at the bottom of the frame on account of the strip 28, which firmly engages the glass, and water will be prevented from entering around the sides of the sash by means 75 of the packing-strips 21, which engage the sides of the glass. However, the sash may freely slide up and down, and when in either its upper or its lower position water will be prevented from entering the opening in the bottom of the window-frame. When the forward sash is at its lower limit of movement, then the overhanging strip 23 will give additional protection and water will be prevented from 80 entering said opening. One of the principal 85 objects in providing a double window-frame of this kind is to exclude cold air, and it is obvious that when the outer sash is in its closed position the same packing-strips will prevent the entrance of cold air. Furthermore, 90 the space between the two panes of glass is stopped, so that air cannot circulate through it when both sashes are closed by the upper and lower strips of the inner sash engaging the 95 mating strips of the outer sash.

In the modified form illustrated in Fig. 3 I have shown a structure in which each sash is divided into two parts, one of which is capable of moving upwardly and the other downwardly. The top window-frame is provided with a number of openings wide enough only to allow the glass of the upper sashes to pass through them, and the bottom of the window-frame is made exactly like the one illustrated and described in connection with Fig. 1 of the drawings. In this modified form the outer sash is composed of two parts. The upper part has its frame composed of a top piece 40, into which the glass 41 is fitted, and a bottom composed of an inner strip 42 and an outer strip 43, with the glass 41 admitted between said strips from the top and a rubber packing-strip 44 admitted between said strips 42 and 43 from the bottom and projecting slightly below the bottom. A rope 45 is attached to the strip 40 and passes over a pulley 46, so that a weight may be attached to its other end to counterbalance the weight of the upper sash-section. The lower portion of the outer sash comprises an upper frame-piece 47, into which the glass 48 is fitted, and the lower frame-piece comprises an inner strip 49 and an outer strip 50, with the glass admitted between said strips. The top of the outer strip 50 engages the under portion of 105 110 115 120 125 130

the sill 11 when the lower sash-section is at its upper limit of movement. The side pieces of these sash-sections are arranged the same as in my preferred form just described.

5 Hence it is not necessary to describe them here in detail. In this modified form the inner sash is also composed of an upper and lower section arranged substantially like the upper and lower section of the outer sash.

10 The glass for the upper section of the sash is indicated by the reference-numeral 51 and that for the lower section by the reference-numeral 52, the said upper section being provided with a rope 53, passed over a pulley 54.

15 In this form of the device the screen is also composed of an upper and lower section, the upper section sliding upwardly through the top of the window-frame and indicated by the reference-numeral 55 and the lower section

20 sliding downwardly and indicated by the reference-numeral 56. In other respects the construction and operation of this modified form are substantially the same as in the preferred form before described.

25 Referring to Figs. 4, 5, and 6 of the drawings, I have shown another modification of my invention, in which the window sashes and screen are arranged to slide horizontally instead of vertically. Referring to said drawings, I have used the reference-numeral 58 to indicate a rectangular window-frame of the ordinary kind except that the bottom piece is provided with a slot 59, through which the glass of the outer sash may slide, and one of

35 the side pieces is provided with a slot 60 for the same purpose. At the top of the window-frame are the stops 61, of ordinary construction, to guide the several sashes and screen-frame, and at one side of the window-frame are the stops

40 62, of ordinary construction, and at the opposite side the sashes pass through the slots 60 into an opening provided in the wall for that purpose, said opening having stops 63 at its top and stops 64 at its bottom edge to serve as guides

45 for the sashes and screens. In the bottom of the window-frame 58 and beneath the slot 59 therein is a frame 65 to slidingly support the bottom of the outer sash, and this frame continues under the opening in the side wall provided to receive the sashes, as clearly indicated in Fig. 5. The frame of the outer sash is indicated by the reference-numeral 66 and the glass by the reference-numeral 67. The said glass passes through the slot 59 in the bottom of

55 the frame and also through the slot 60 at one side of the frame. The lower portion of the sash-frame 66 rests in the frame 65, and a packing-strip 68, resting on top of the bottom part of the frame 58, engages the front of the

60 glass 67 to prevent the entrance of cold air when the sash is in its closed position. The reference-numeral 69 indicates the second sliding sash, which is like the first except that its lower portion rests on top of the bottom portion of the frame 58 and between the stops 70.

The reference-numeral 71 indicates the screen-frame, which is an ordinary rectangular frame resting between the stops 61 at its top and the stops 70 at its bottom edge and passing through one of the slots 60 at the side.

The essential features of my invention and the one common to both of the modified forms shown are briefly the arrangement of the outer sash, in which parts of its frame enter casings having openings therein large enough to permit the glass to pass through them, so that a tight joint at this point is provided to prevent the admission of moisture or cold air. Another feature which all of the forms have in common is that the lower portion of the outer-sash frame stands beneath the sill and a packing-strip fixed to the sill engages the glass, thus preventing the entrance of moisture or cold air at the bottom of the sash.

Having thus described my invention, what I claim, and desire to secure by Letters Patent of the United States therefor, is—

1. In a device of the class described, the combination of a window-frame, a casing secured to the window-frame and having a narrow slot 90 therein, a window-sash having a glass panel slidingly mounted in the frame, one side of the window-sash resting in said casing with the glass panel projecting through the slot thereof.

2. In a device of the class described, the combination of a window-frame, casings at the sides of the frame having slots therein, an outer sliding sash in the window-frame having a glass panel, the sides of said sash sliding in said casings and the glass in the said sash projecting through the slots in the casings, an inner sliding sash in the window-frame, having a glass panel therein and having its upper and lower ends in engagement with the upper and lower ends of the outer sash when both are in their closed positions and a sliding screen in the window-frame, having its upper and lower ends in engagement with the upper and lower ends of the inner sliding sash when both are in their closed positions.

3. In a device of the class described, the combination of a window-frame, casings at the sides of the frame having slots therein, an outer sliding sash in the window-frame having a glass panel, the sides of said sash sliding in said casings and the glass panel thereof projecting through the slots in the casings, an inner sliding sash in the window-frame having a glass panel therein and having its upper and lower ends in engagement with the upper and lower ends of the outer sash when in its closed position and a sliding screen in the window-frame having its upper and lower ends in engagement with the upper and lower ends of the inner sliding sash when in its closed position.

4. In a device of the class described, a window-frame, a slotted casing at each side of the window-frame, a sliding sash having a glass

panel, the sides of the sash mounted in the casings and the glass panel projected through the slots of the casings, the top portion of the sash-frame cut away near its ends, a sill in the 5 window-frame projecting over the bottom of the sash and a strip on said sill engaging the front of the glass panel.

5. In a device of the class described, the combination of a window-frame, a slotted casing at 10 each side of the window-frame, a sliding sash having a glass panel, the sides of said sash mounted in the casings and the glass panel projecting through the slots of the casings the top of the sash-frame near its ends notched, 15 a sill in the window-frame projecting over the bottom of the sash, a strip on said sill engaging the front of the glass panel and a flexible packing-strip on each casing adjacent to the slot thereof and in engagement with the glass 20 panel.

6. In a device of the class described, the combination of a window-frame, a slotted casing

at each side of the window-frame, a sliding sash having a glass panel, the sides of the sash mounted in the casings and the glass panel 25 projecting through the slots of the casings and the top of the sash notched near its ends, a sill in the window-frame projected over the bottom of the sash-frame, a strip on said sill engaging the front of the glass panel, a second sliding sash in the rear of the first having 30 a glass panel and a sash-frame, the upper and lower portions of the second sash-frame engaging the corresponding portions of the first sash-frame, a third sliding frame in the rear 35 of the second having its upper and lower portions in engagement with the corresponding parts of the second sash-frame, counterbalancing-weights for the first and second sash-frames, and a stop for the third or inner frame. 40

GUSTAF WAHLSTROM.
